UNITED STATES PATENT OFFICE

HARRY E. KECK, OF PITTSBURGH, PENNSYLVANIA

APPARATUS FOR ICING LAYER CAKES

Application filed September 21, 1928, Serial No. 307,415. Renewed September 26, 1931.

This invention relates to a device for depositing and spreading icing or filling on cakes and the like.

In order to obtain an icing that will properly flow through spraying nozzles for automatic application to the surface of a cake, it is necessary that the icing be a boiled icing. Filling material, used between two or more layers of cake, is generally very viscous, and for this reason has never been satisfactorily distributed on cakes by the use of automatic machines. Heretofore, it has been necessary to spread filling material, or uncooked frosting by hand, and it has been found that this method results in a great waste of material and labor.

The object of this invention is to provide apparatus for automatically distributing frosting on cakes.

A further object of the invention is to provide an apparatus which will deposit filling material on a cake layer, and which will thereafter distribute frosting on the assembled layer cake.

In the accompanying drawings Figure 1 is a plan view of a table showing the arrangement of means for filling and icing cakes; Figure 2 is a fragmental front elevation of the table and the two operating heads of the device; Figure 3 is a rear elevation of the machine; Figure 4 is a sectional view through the machine, taken on the line 4-4 of Fig. 3; Figure 5 is an enlarged sectional view taken on the line 5-5, Fig. 1, showing to advantage the detailed structure of the icing head; Figure 6 is an enlarged plan view of the icing head and its supporting means; Figure 7 is an end elevation of the same, the rotary head portion is turned through a 90 degree angle from the position shown in Fig. 6; Figure 8 is a sectional view through the rotary part of the head, taken on the line 8-8, Fig. 6; and Figures 9, 10, and 11 are views similar to Figs. 5, 6, and 8 respectively, showing a modified arrangement of the head for frosting square cakes.

The reference numeral 1 denotes a table on which the operative elements of the machine are mounted. A conveyor belt 2 serves to feed the cakes to the table 1 where an oper-

ator handles them during the filling and icing process, and a belt 3 serves to remove the completed cakes.

The machine will be described as it is used in the assembling and icing of cakes, but it is to be understood that should it be desirable to frost cakes of a single layer the filling portion of the said machine may remain idle, and only the icing head caused to operate. In large bakeries, where a great variety of cakes are made, it may be desirable to utilize a machine having the icing head alone.

Arranged to overlie the table are two rotatable heads 4 and 5. Head 4 deposits and spreads the filling material on a layer of cake positioned thereunder. The operator then places another cake layer thereon and places the assembled cake under the icing head 5 where the cake is frosted. Since the combination of elements which supplies the filling material to head 4 is identical with that which feeds and drives the icing head 5, only one of such portions will be described in detail.

Each head has a piped connection to a supply tank, the filling head 4 being associated with a tank 6 which retains the filling material, mixed and ready for use. Each tank, such as tank 6, is arranged with a heavy head 6a which fits snugly within the walls of the tank and rests on the material contained therein. Connected by a pipe L 7 to said tank is a plunger pump 8 which, assisted by the head 6a, removes the filling material from the tank 6 and forces it to the head 4 through the flexible pipe line 9. In order that the correct amount of material may be deposited on the cake, a valve 10 is positioned as illustrated to control the flow of the said material from the tank 6 to the head 4. Both the valve 10 and the plunger of the pump 8 are operated by the double track cam 11, and this allows a simple adjustment of the cam engaging link 12 on the plunger rod 13 to properly synchronize the movement of the said valve and plunger. The rod 10a rides the cam 11 and serves to throw the valve 10. The said adjustment will also establish the travel of the pump plunger, which in turn determines

the amount of material expelled from the head 4.

As may be seen in Figure 4, the cam 11 is fixed to shaft 14 which is driven by any suitable connections to a source of motion. In the drawings the said shaft is driven by means of a sprocket wheel 15 meshing with sprocket chain 16. Motion is transmitted to the said chain through mechanical connection, such as sprocket wheel 15a, to the revolving shaft 50 which is driven by a belt 51 coming from a suitable source of power. As illustrated this shaft is belted, or rotatably chain connected, to the shaft 2a of the 10 endless belt conveyor 2. A long chain or belt 52 serves to transmit the rotation of shaft 50 to the driving elements of head 5. That is, the chain 52 causes the shaft 53 to revolve similarly to the shaft 50 on the filling head 20 end of the machine. The tubular arm 17 supports the head 4, and it is fixed to a frame 18 which is mounted to slide vertically in the frame 19. The latter frame is fixed to the table 1. Normally the position of the head 25 is raised, as shown in dotted lines in Fig. 4, and the operative position is shown in full lines. There is fixed to the frame 18 a vertical arm 20 which rides on the face of cam 21 as the latter revolves with shaft 14 to which 30 it is affixed.

Since it is desirable that the head 4 should not rotate continuously, means are introduced which permit rotation to occur only during the time the head is in its lowered position. Arranged in the frame 18, and mounted on the vertical shaft 22 is a pulley 23. To the same shaft is fixed the disk clutch portion 24. On a similar shaft 25 is keyed the lower clutch portion 26 which rotates continuously due to the bevel gear 27 meshing with the bevel gear 28 on shaft 29. The large spur gear 30 which is fixed to the shaft 14 meshes with the gear 31 and serves to rotate the clutch portion 26 at a relatively great speed. As all of the automatic movements of the head 4 and its associated elements originate at the shaft 14 it may readily be seen that the timing of the various movements may easily be resolved or adjusted.

50 A layer of cake A is placed or delivered on the table beneath the head 4 when the same is in its raised position. As the shaft 14 revolves, the cam 21 allows the rider arm 20 to drop and consequently lowers the head 4 to the cake layer A. As the filling head 4 reaches this position, the cam 11, being properly timed, causes the valve 10 and pump 8 to function. As a result, a charge of filling material is squirted through the head 4 and upon 55 the cake layer A. The lowering of the said head is accompanied by the engagement of the two clutch members 24 and 26, and this engagement causes the pulley 23 to revolve which, due to the driving belt 32 imparts a 60 spinning movement to the head 4 approxi-

mately at the same time that filling material is ejected therefrom. This action aids in the even distribution of the filling on the cake layer, but the spreading strips 33 give a final levelling of the material.

The structure of the two heads 4 and 5 is very similar, the chief distinction being that the icing head 5 has one or more vertical spreading strips with which to ice the sides of the cake. After the filling head 4 has completed its operation, another layer of cake is superimposed on the cake layer A. The assembled cake B is then placed beneath the icing head 5 which is shown in detail in Figures 5, 6, and 7.

The structure of the head is unique in operation; the structure is further desirable in that it is readily taken down for cleaning. The icing flows through the tubular arm 17 to the space 17a above the rotary portion of the head. It is preferable to form the entire mechanism of aluminum, but as aluminum does not slide well on aluminum unless an abundance of oil is used, and as oil cannot be used near the icing or filling material, it should be noted that a bronze ring 33 is arranged on the arm 17 where it abuts a steel ring 34a fixed to rotary portion 34 of the head 5. These two rings of unlike metals may be drawn into close engagement and will revolve with little or no lubrication. This serves to give a tight jointure between the stationary and rotary portions of the head proper, and no leakage of the filling or icing material occurs. A shaft 35, having a threaded engagement with the head portion 34, extends upward through opening 17a, and through the upper wall of arm 17 and the threaded bearing plate 36. The wing nut or hand wheel 37 may be tightened after the desired tightness between the fixed and rotatable members of the head has been obtained by rotating the plate 36. The two races of ball bearings 55 and 56, positioned as shown, merely serve to reduce the frictional losses. The parts, as seen, may be easily disassembled for cleansing.

The head portion 34 includes two hollow legs 34a and 34b, and at the outer end of each leg is a circular aperture for the reception of tube members 38 and 39 respectively. Suitable means, such as clamps 40, may be employed to retain the members 38 and 39 in place. It will be noticed that the interior of the arm 17, and the two legs 34a and 34b, and the side or end tubes 38 and 39 present a continuous opening in which the icing material rests. The pipes leading from the supply tank and pump, and the hollow regions last mentioned, are completely filled with frosting before the head ejects any material on the cake.

To the under surface of the legs 34a and 34b are affixed flexible spreading strips 41 and 42; and arranged in suitable supporting

means, as shown in Fig. 5 of the drawings, are similar vertical strips 43 and 44. These resilient spreading members are preferably composed of a highly flexible material, such as 5 high grade rubber, celluloid strips, or a relatively stiff fabric. As their function is to distribute evenly the icing material deposited on the cake, they must be very resilient in order to follow the general contour of the cake surface. As seen in Fig. 8 of the drawings, the strips 41 and 42 are desirably fixed to the portions 34a and 34b by means of screws 47 and wing nuts 48. The portions 41a and 42a of the strips 41 and 42 have slots 49 through 5 which the screws 47 pass, and on the under side of said portions the metal strips 50 having slots 51 serve as a washer for the several wing nuts 48. As may readily be seen, the edge 52 of the strips 41 and 42 may be moved 10 to cover part of the openings 45. This serves as a means for adjusting the cross sectional area of said openings 45. When a frosting of less viscosity is being used the members 41 and 42 may be moved to cover a portion of the 15 orifices 45, and in this way the proper amount of material may be made to flow therefrom.

The manner in which the frosting is deposited on the cake is of great importance. If the coating varies in thickness on different 10 cakes the product is not uniform, and the result would reflect in the good will of the purchasers. Also, it is desirable to put a coating on the cake of such a thickness that the costly frosting will not be wasted. For the above reasons the arrangement of orifices 45 on the underside of the legs 34a and 34b is 15 of prime importance.

Due to the variance in velocity, as found 20 in all angular movement, between the center and outer points of the icing head legs, it is considered very essential that the openings should increase in size directly in proportion to the distance from the center of rotation. The orifices in the leg 34a are spaced 25 radially in such a manner that the circles described by their rotation lie, or fill the space between, the similar circles described by the orifices in the leg 34b. This interrelation of the orifice positions permits the frosting or 30 filling material to cover all points of the upper surface of the cake. The openings are shown herein as a plurality of orifices which need not of necessity be aligned, but the use of a divergent slot may probably be employed as an equivalent. The real theory is 35 that the material emitting area increases in proportion to the distance from the center of rotation, and this may be accomplished in several ways. It is found desirable to have the orifices 45, or other openings, placed adjacent the spreading strips, such position may possibly, however, be varied successfully by subsequent experiments.

Orifices 46 in the vertical members 38 and 39 allow the icing material to reach the sides 40 of the cake. The orifices in the member 38 are vertically spaced between the paths generated by the orifices in the member 39. This allows the icing to completely cover the side 45 of the cake when the head rotates and emits 46 said icing material. As previously explained, before the head 5 is ready to operate the icing material is pumped into the hollow regions of the head and its member 34a, 34b, 38, and 39, and when a cake B is placed under the head 50 on table 1, the head lowers as the plunger moves to effect the ejecting of the desired amount of frosting through the several orifices upon the cake. Of course, the clutch members 24 and 26 are engaged to rotate the 55 said head during the time the frosting is being ejected, and the spreading strips serve to evenly distribute the frosting.

The head 4 which is used to perform the filling operation is practically the same as 55 the head 5. As the filling material is placed only on top of the cake layer A, it is obvious that the side tubes such as 38 and 39 are not needed. In other respects the structure and 60 operation of the filling and icing heads, 4 and 5 respectively, are the same. It should be understood, however, that the icing head may be employed as a unit machine, or it may be tandem with a filling head to form two 65 cooperating units on a machine to fill and ice 70 layer cakes.

Figures 9, 10, and 11 show a slightly modified head structure to be used in icing, or filling and icing square cakes. Obviously a rotary head cannot be used in icing square 75 cakes, but the principles disclosed in conjunction with the revoluble heads may be employed in frosting square cakes. In order to adapt the machine as a whole for icing a square cake, it is simply necessary to remove the belt 32 and the rotary head portion 34. A generally similar head portion 60 is mounted in the place of the removed head portion 34. Since the substituted head 60 should extend across a square cake D, as 80 shown in Fig. 10, it is desirable to have means, such as set screws or pins 61, mutually engage the said head member 60 and the stationary head portion 17 to prevent rotation of the former. If it is not necessary that the head 85 elements should rise and fall, the arm 20 may be removed from the cam 21, and the head allowed to remain in its lowered operative position.

The head portion 60 has the same general 90 shape as the head 34. The orifices of the latter are replaced by a slot 62 which extends across the two legs 60a and 60b, and it is of uniform width throughout its length. Orifices of uniform cross section may be arranged 95 in close alignment in place of the slot, but either the orifices or the slot 62 should be arranged adjacent the resilient spreading strips 63 as shown in Fig. 11.

The side strips 64 and 65 are fixed in side 100

tubes 66 and 67 which resemble the tubes 38 and 39 of the principal head 34. The cake D is pushed, or fed on an endless belt or other suitable means, in the direction of the arrow in Fig. 10, and the icing material is fed upon the cake by the same movement of the valve and pump as has been explained herein. Fig. 11 shows the cake D passed half way under the head portion 60 and shows 10 how the frosting 68 is smoothed upon the cake.

What I claim is:

1. In a machine for frosting cakes and the like a rotary head serving as a reservoir for frosting, driving means for rotating the same, said head having orifices therein to emit frosting material, and feeding means for intermittently supplying said material to the head, together with synchronized means for 15 rendering said head-driving means and said feeding means effective.

2. In a machine for frosting cakes and the like a rotary head serving as a reservoir for frosting, means for rotating the same, said head having openings therein to emit frosting material, the area of said openings increasing in proportion to their distance from the center of rotation of the head, and means for supplying said frosting material to the 20 head.

3. In a machine for frosting cakes and the like a rotary head serving as a reservoir for frosting, means for rotating the same, said head having openings therein, the area of 25 said openings increasing in area proportionately to their distance from their center of rotation, and means to automatically supply frosting to the head and thereby expel it from said opening at fixed intervals.

4. In a machine for frosting cakes and the like a rotary head serving as a reservoir for frosting, means for rotating the same, said head having orifices therein to emit frosting material, and flexible spreader strips arranged to rotate with said head.

5. In a machine for frosting cakes and the like a rotary head serving as a reservoir for frosting, flexible spreader strips affixed thereto, said head having orifices therein, the areas 30 of said orifices increasing in magnitude in proportion to the distance from their center of rotation, means for rotating said head, and means to supply frosting to the head and thereby expel it from said orifices.

6. In a machine for frosting cakes and the like a table, a spreading head slidably mounted for vertical movement thereon, said head having orifices therein to emit frosting material, a tank for frosting material, a pump affixed to said tank, a control valve in said pump, pipe connections from said pump to said operating head, driving means for rotating said head, feeding means for forcing frosting material from said tank 35 to said head, together with synchronized

means for rendering said head-driving means and said feeding means effective.

7. In a machine for frosting cakes and the like a table, a rotatable head mounted vertically slidably thereon, said head having orifices therein to emit frosting material, a container for frosting material, tubular connections between said head and said container, means for feeding the said material from the container to the said head, automatic means for lowering the head into operative position, and mechanical elements to rotate the said head in its lowered position, together with synchronized means for rendering said feeding means, said automatic means, and said mechanical elements effective.

8. In a machine for frosting cakes and the like a table, a rotatable head slidably mounted for vertical movement thereon, said head having orifices therein to overlie the top and sides of a cake, a container for frosting material, tubular connections from said head to said container, automatic means for lowering the head into operative position, and mechanical elements to rotate the said head in its lowered position.

9. In a machine for frosting cakes and the like a table, a rotatable head slidably mounted for vertical movement thereon, said head having orifices therein and resilient spreader strips thereon to overlie the top and sides of a cake, a container for frosting material, tubular connections from said head to said container, automatic means for lowering the head into operative position, and mechanical elements to rotate the said head in its lowered position.

10. In a machine for frosting cakes and the like a table, a rotatable head mounted thereon, said head having orifices therein, the areas of said orifices increasing in proportion to their distance from their center of rotation, flexible spreader strips arranged on the said head to brush the cake, a container for frosting material, means for feeding said material to the said head, and mechanical elements to rotate head.

11. In a machine for filling and frosting cakes, a table, conveyor belts operatively arranged at each end thereof, a tank to contain filling material, connections from said tank to a rotatable head mounted vertically slidably on said table, a second tank to contain icing material, connections from said tank to a second rotatable head mounted vertically slidably on said table, means for lowering said heads into operative position, means for rotating the same in their lowered position, and adjustable means to feed the material from the tanks to their respective heads, openings in said head to expel the material therefrom, and the areas of said openings increasing in cross section proportionately to their distance from their center.

of rotation, flexible strips arranged on said heads to distribute the deposited material.

12. In a machine for frosting cakes and the like a rotary head, means for supplying frosting to said head, frosting emitting openings in the head to emit frosting material, adjustable spreader strips adjacent the openings, and means for varying the area of said openings.

13. In a head for frosting cakes and the like a rotary head, tubular side members extending downwardly from said head, means for supplying frosting to the head and its side members, frosting emitting openings on the head and side members, spreader strips arranged adjacent the openings, and means for varying the effectual area of the said openings.

In witness whereof I hereunto set my hand.

HARRY E. KECK.
